(57) **CLAIM**

The ornamental design for a hospital gown cover, as shown and described.

DESCRIPTION

FIG. 1 is a perspective view of the hospital gown cover being worn by a patient;

FIG. 2 is a back view of the hospital gown cover;

FIG. 3 is a front view of the hospital gown cover;

FIG. 4 is a first side view of the hospital gown cover;

FIG. 5 is a second side view of the hospital gown cover; and, FIG. 6 is a top view of the hospital gown cover.

The broken lines depicting the human form shown in the drawings are for environmental structure only and form no part of the claimed design.
